DESIGN FOR A MILLING MACHINE

Richard K. Le Blond and Harry C. Kemper, Cincinnati, Ohio, assignors to The R. K. Le Blond Machine Tool Company, Cincinnati, Ohio, a corporation of Delaware

Application June 2, 1941, Serial No. 101,262

Term of patent 14 years

To all whom it may concern:

Be it known that we, Richard K. Le Blond and Harry C. Kemper, citizens of the United States and residents of Cincinnati, county of Hamilton and State of Ohio, have invented a new, original, and ornamental Design for Milling Machine, of which the following is a specification, reference being had to the accompanying drawings, forming part thereof.

Figure I is a front elevational view of the milling machine incorporating our new design.

Figure II is a plan view of the milling machine shown in Figure I.

Figure III is a left hand end elevation of the milling machine shown in Figure I.

Figure IV is a right hand end elevation of the milling machine shown in Figure I.

Figure V is a rear elevational view of the milling machine shown in Figure I.

We claim:

The ornamental design for a milling machine, substantially as shown.

RICHARD K. LE BLOND.
HARRY C. KEMPER.
